UNITED STATES PATENT OFFICE.

ALEXANDER P. WADDELL, OF UNION CITY, TENNESSEE, ASSIGNOR OF ONE-HALF TO WM. HENRY MILLER, OF LITTLE ROCK, ARKANSAS.

TRACE-CARRIER.

SPECIFICATION forming part of Letters Patent No. 429,369, dated June 3, 1890.

Application filed October 7, 1889. Serial No. 326,200½. (No model.)

To all whom it may concern:

Be it known that I, ALEXANDER P. WADDELL, of Union City, in the county of Obion and State of Tennessee, have invented a new and useful Improvement in Buckles, of which the following is a specification.

My invention is an improvement in buckles and especially in that class of buckles designed for use as trace-carriers; and the invention consists in certain features of construction and novel combinations of parts, as will be hereinafter described and claimed.

In the drawings, Figure 1 is a perspective view of the buckle. Fig. 2 is a sectional view of the buckle with the strap applied, and Fig. 3 is a perspective view of the buckle with the strap and chain applied.

The buckle is formed with a plate or frame-work A, slotted or otherwise suitably constructed to provide the single cross-bar B at its lower end and the cross-bars D and E at its upper end, slots or spaces b, d, and e being provided adjacent the said cross-bars for the passage of the back-strap F, preferably made of heavy drilling. A number of short spurs G project from the rear face of the plate or frame-work A, immediately above the slot b, the said spurs being preferably ranged in a series across the plate or frame-work, parallel with and just above the said slot b, as shown.

On the front face of the plate or frame-work A is provided the hook H, opening upwardly, as shown, so that it will properly support a trace by suspending one of its links thereon. To secure the chain-link in engagement with the hook H, I provide retaining-hooks h h, arranged above and in lines on opposite sides of the hook H, the said hooks h opening in opposite directions to the hook H—that is to say, downwardly—while the hook H opens upwardly, as shown and before described. It will also be seen that the interior of the hooks H h are approximately concentric, so that the side bar of a link turned horizontally in the link-keeper formed by hooks H h will be snugly held therein. It will also be seen that by turning the link vertically it may be conveniently adjusted into or out of such keeper, as will

be understood from the drawings. When turned horizontally in the keeper formed of hooks H h, the retaining-hooks h h prevent the accidental displacement of the chain-link and secure the same in engagement with the hook H until such link is turned vertically, when it can be easily slipped out of engagement, as may be desired. The strap F is passed from back to front through slot d, thence over cross-bar E, and from front to back through the slot e, thence down the rear side of plate or frame-work A, around the lower edge or cross-bar B, thence through slot b, from front to rear and up between the plate or frame-work A and the portion of strap F, extended down from slot e, the said inner or intermediate portion of the strap being engaged by the spurs G, which are so short that they do not extend through the strap, yet are sufficiently long to hold the strap securely, inasmuch as the strain thereon is largely taken up by its numerous coils through and around the plate or frame-work A. To take up the strap, slack may be taken through the slots and its free end drawn up, and, if drawn through the slot e, may be left to hang over the link-keeper H h, or may be passed on to rear through slot d.

The double arrangement of strap in rear of the buckle-plate or frame-work forms a pad and prevents the buckle from injuring the side of the horse, which pad may be increased by placing a slip of any suitable material between the double of the strap on rear, said slip to extend from slot e to slot b. This will effectually prevent the spurs from making impression on the horse's side in case of back-strap being of thin material.

Having thus described my invention, what I claim as new is—

1. The improved buckle herein described, comprising the plate or frame-work having cross-bars at its upper and lower end, and provided on its front face with the hooks H and h h, all substantially as and for the purpose set forth.

2. The improved buckle herein described, comprising the plate or suitable frame-work A, having cross-bars B D E, provided on its rear side above cross-bar B with spurs G,

100

and having a trace-link receiver or support, substantially as set forth.

3. The improved buckle herein described, consisting of the plate or frame-work A, having cross-bars B, D, and E, provided on its rear side above cross-bar B with spurs G, and provided on its front side with the link-keeper formed of hook H and the hooks h h, arranged

above and on opposite sides of the hook H, all substantially as and for the purposes set forth.

ALEXANDER P. WADDELL.
